[57] CLAIM

The ornamental design for an elongated frame revolver, substantially as shown and described.

DESCRIPTION

FIG. 1 is a left side elevational view of the revolver of the present invention;

FIG. 2 is a right side elevational view thereof;

FIG. 3 is a top plan view thereof;

FIG. 4 is a front elevational view thereof;

FIG. 5 is a bottom plan view thereof;

FIG. 6 is a rear view thereof; and

FIG. 7 is a left-hand side perspective view.

The broken line showing of the scope is for illustrative purposes only and forms no part of the claimed design.
